UNITED STATES PATENT OFFICE.

GEORGE H. POTWIN, OF CHICAGO, ILLINOIS, ASSIGNOR TO ACCOUNTING DEVICES COMPANY, OF CHICAGO, ILLINOIS, A CORPORATION OF ILLINOIS.

LOOSE-LEAF DEVICE.

1,351,487.

Specification of Letters Patent. Patented Aug. 31, 1920.

Application filed May 24, 1918. Serial No. 236,309.

To all whom it may concern:

Be it known that I, GEORGE H. POTWIN, a citizen of the United States, residing at Chicago, in the county of Cook and State of Illinois, have invented a new and useful Improvement in Loose-Leaf Devices, of which the following is a specification.

This invention relates particularly to means for supporting loose-leaf books such as loose-leaf ledgers, to facilitate the work of posting, or making entries, by means of a typewriter, or a tabulating machine, or some analogous purpose.

The primary object is to provide a device for supporting a loose-leaf ledger, or the like, which will facilitate the work of manipulating the sheets in the operation of posting or making entries, and then re-assembling the leaves in the book.

20 Binder-supporting racks of W-form are on the market and are being used to some extent. Among other objections, they require a long reach on the part of the operator sitting in front of a typewriting machine to obtain the sheets, and require movements in manipulation which are awkward. The leading object of the present invention is to provide a compact device which may be placed at one side of the typewriting machine, which will enable the sheets to be easily reached, which will avoid awkward manipulations in introducing the sheets into the typewriter and returning them to the rack, and which will facilitate the work 35 of binding the sheets again in the binder.

40 A further object is to provide a loose-leaf device in which a loose-leaf binder and a supporting rack therefor are so arranged and combined as to enable the loose sheets comprising a ledger, or the like, to be manipulated with the utmost facility, in order that machine entries or machine posting may be effected expeditiously, and in order that the whole work of taking the sheets 45 from the binder, effecting the machine entries, and re-binding the sheets may be performed with the utmost efficiency.

The invention is illustrated in its preferred embodiment in the accompanying 50 drawings in which—

Figure 1 represents a side-elevational view of a loose-leaf book-rack constructed in accordance with the invention, the view showing one portion of a loose-leaf book supported on a lower platform and another por-

tion of the loose-leaf book supported on an upper platform; Fig. 2, a plan view of the same, a portion of the upper platform broken away; Fig. 3, a broken side elevational view, showing a modification in which the lower platform is adjustable; Fig. 4, a perspective view of the construction shown in Fig. 1, the rack being viewed from a point in front and at one side thereof; Fig. 5, a broken view showing a modification in which the upper platform, or ledge, is adjustable; Fig. 6, a broken sectional view of a binder of a form in connection with which the improved rack is well adapted to use; and Fig. 7, a broken sectional view taken as indicated at line 7 of Fig. 6.

Describing Figs. 1, 2 and 4, A represents a frame comprising a base A¹ and a standard A² rising from the rear end of the base; B, a lower platform mounted on the front portion of the base and disposed in front of the lower portion of the standard A²; and C, an upper platform, shelf, or ledge which projects forwardly from the standard, and which is disposed above the rear portion of the platform B.

In the construction being described, the lower platform B is supported by wedge-shaped side-members 1 mounted on the base A¹ in such manner that the platform inclines rearwardly and downwardly. The standard A² is shown as comprising uprights, or side-members, 2, connected at their upper ends by a cross-member 2^a. The members 2 have upwardly and rearwardly inclined front edge-surfaces 2^b which continue down to the point of junction with the lower rear end of the platform B. The shelf C, which may have a rearward extension C¹ firmly secured between the side-members 2 of the standard, preferably forms an acute angle at its upper side with the inclined faces 2, the purpose being to cause the leaves, supported on edge on the platform C, to be "fanned" at the upper edges to facilitate the removal of the leaves, one at a time, or in bunches, as desired. Below the base-portion of the upper platform C is a rearwardly and upwardly inclined wall 3, which is provided at an intermediate point with a rib, or guide, 3^a. The wall 3 is recessed or cut away at its lower portion to afford a recess, or groove, 3^b, at the point of junction with the lower platform B; and at one lateral edge of the wall 3 is a re-

cess, or groove, 3^c. The recess 3^b is adapted to receive therein one edge of a binder-section, while the lower portion of the recess 3^c is adapted to accommodate the clamping-member of said binder-section, which usually is thicker than the cover-section. At the base-portion of the upper platform C, on the upper side thereof, is provided a groove, or recess, 4, which extends across the platform and is adapted to accommodate the edge of a binder-section. This groove may be wide enough at one end to accommodate a clamping member of the binder-section, and through the main portion of its length may be sufficient only to accommodate the edge-portion of the cover-section.

The construction described has the lower platform B and the upper platform C occupying a stepped relation, thus affording a lower receptacle D adapted to support a book on its side and an upper receptacle E adapted to support a book on edge.

In Figs. 6 and 7 is illustrated a loose-leaf binder, for use in connection with which the improved rack is well adapted. The binder shown comprises an upper cover-section F equipped with a pivotally-connected clamping-member F¹; a lower cover-section G equipped with a pivotally-connected clamping-member G¹; and binding-posts H releasably locked to the clamping-members. In the illustration given, the clamping-members are shown equipped with ball-locks 5, which are engaged by the forked ends of spring-held levers 6 mounted in the clamping-members. In the illustration given the levers 6 in the upper clamping-member are equipped with push-buttons 6^a by means of which the levers may be actuated to release the balls from binding engagement with the posts; and the levers 6 in the lower clamping-member are adapted to be actuated by sliding-cams 6^b, whereby the levers may be actuated to release the balls from binding engagement with the lower ends of the posts. Either construction provides releasable locking connection between the binding-members and the posts, so that the posts are removable from the binder. In Figs. 1 and 2, the leaves of the book are designated I; and one part of the book is shown supported on edge on the upper platform C, while the other part of the book rests flatwise on the lower platform B. The leaves are shown provided at their ends with round perforations 7, and at their bottom edge with grooves or U-shape openings 8. In Fig. 2, a method of offsetting some of the leaves is illustrated in the right-hand portion of the figure.

The manner of using the improved device may be described briefly. Assuming the use of a binder of the character illustrated, the book may be stood on edge upon the upper

platform C, with the lower cover-section G reclining against the inclined surfaces 2^b, the bottom edge of the cover-section and its clamping-member being accommodated by the groove 4. By manipulating the push-button 6^a, the upper cover-section is then removed and laid upon the platform B, with the clamping-member F¹ thereof projecting into the lower portion of the lateral recess 3^c of the rearwardly-inclined wall 3. Assuming the binder to occupy a position at the right of a typewriter, for instance, the operator is able to view the name appearing at the upper edge of the sheet; and the operator may, with facility, reach over the platforms B and C and remove the sheets, as desired, from the receptacle E. Such sheets as require no entries are immediately placed upon the cover-section F, in proper turn; and such sheets as require entries are introduced into the typewriting machine, or tabulator, as the case may be, and the proper entries are made, after which the sheets are placed, in proper order, upon the stack of sheets accumulating in the receptacle D. The sheets when thrown into the receptacle D gravitate readily to the desired position, the groove 8 of the sheet engaging the rib 3^a of the rack. The rib 3^a of the rack is so spaced with relation to the shoulder afforded by the lateral groove 3^c as to bring the perforations 7 of the sheets in alinement with the post-receiving sockets of the clamping-member F¹ of the binder. In case it is desired to offset any of the sheets, this may be accomplished in the manner illustrated in Fig. 2; and after the proper tabulating has been performed, the offset sheets may be shifted over to the proper stacked relation. The binding-posts may then be entered through the sheets, and will be automatically locked to the clamping-member F¹, after which the cover-section G may be applied, and the clamping-member G¹ will be automatically locked to the binder-posts.

It is desirable, ordinarily, to have the platforms B and C incline rearwardly and downwardly; and ordinarily it is desirable to provide rearwardly and upwardly-inclined walls as backing-portions for the receptacles D and E. However, the arrangement may be varied. In Fig. 3 is illustrated a construction in which the lower platform B¹ is adjustable, and may occupy a horizontal position. In this case, the platform is shown connected to the frame by a pivot 9 and equipped with pivotally-connected arms, or pawls, 10, adapted to engage lateral horizontal racks 11 with which the base is equipped, thus providing a platform of adjustable inclination. In some cases, it is desirable to have the platform occupy substantially a horizontal position, and this construction provides for such a result.

In Fig. 1, the upper platform or shelf C is

shown fixed. In Fig. 5, however, the platform C is replaced by an adjustable platform C¹ working in grooves 12 provided in the standards A². The platform C¹ may be of such dimensions as to project as far from the standards as may be desired, depending upon the size of the book. The platform C¹ is shown adjusted so as to project in front of the standard a sufficient distance to receive 10 a thicker book than is provided for in Fig. 1. In this position, the inner edge of the platform engages a shoulder 12^a with which the groove 12 is provided. If desired, however, the platform may be tilted upwardly 15 so that its inner edge will be free from engagement with the shoulder 12^a, and the platform may be then shoved inwardly until its inner edge engages the rear end 12^b of the groove. For certain purposes, it is desirable to have the upper platform adjustable. This is particularly true where the improved rack is to be used in connection with a binder of another type, such as a binder having chain-post connections, or 20 other flexible connections, between its clamping-members. Where the improved rack is used in connection with such a binder, it is desirable to provide appropriate means (not shown) for holding the clamping-member 25 of the upper binder-section, while the lower binder-section is lowered and allowed to rest upon the platform B. Where a binder of the chain-post type is employed, it is unnecessary to employ the central rib 3, as the 30 chain-posts will themselves serve as guides for the sheets, or leaves, of the book. In this case, it may be desirable to have the book, in the first instance, supported on the platform B, and to rest the upper cover- 35 section upon the upper platform C and stack the leaves, after the entries have been made, upon the upper platform against the reclining upper cover-section.

The construction described is simple, and 40 may be cheaply manufactured; and on account of the compactness of the device and the provision for manipulating the leaves in a natural manner, the device is exceptionally well adapted to its purpose. The double-deck, or stepped arrangement of the platforms is an exceedingly desirable feature in the provision of a rack suited to easy manipulation of the leaves in connection with the work of the character suggested. In the 45 illustration given, the arrangement is such as to provide for stacking the leaves in the lower receptacle square with the rack, that is with their lower edges resting against the wall 3. However, this is not an indispensable feature, as provision may be made for stacking the leaves upon the lower platform in any desired manner.

The foregoing detailed description has 50 been given for clearness of understanding only, and no unnecessary limitation should

be understood therefrom, but the appended claims should be construed as broadly as permissible, in view of the prior art.

What I regard as new and desire to secure by Letters Patent is:

70

1. A loose-leaf book-supporting rack comprising a lower platform, a back equipped with a guide-rib for slotted leaves and with a recess at the junction of said platform and back for accommodating a cover-section, and 75 an upper platform having means associated therewith for supporting a book in rearwardly inclined position.

2. A loose-leaf book-supporting rack comprising a lower platform, a back equipped 80 with a guide-rib for slotted leaves and with a recess at the junction of said platform and back for accommodating a cover-section, an upper inclined platform, and means in the rear of said upper platform for supporting 85 a book in rearwardly inclined position.

3. A loose-leaf book-supporting rack comprising a lower receptacle and an upper receptacle arranged in stepped relation thereto, the lower receptacle comprising a platform, an inclined back associated therewith and provided at an intermediate point with a guide-rib and provided at one side of the back with a lateral recess adapted to accommodate the clamping-member of a binder-section, said back being provided at its line of junction with said platform with a recess adapted to accommodate the cover-section, and said upper receptacle comprising 90 an inclined platform and an inclined back, 95 said last named platform being provided at its line of junction with its back with a recess adapted to accommodate a binder-section.

4. A loose-leaf book supporting rack comprising a lower receptacle provided with means for accommodating a binder-section and with guide-means for facilitating the arrangement of leaves in position for binding, and an upper receptacle substantially 100 above the book-space of and in stepped relation to the lower receptacle and comprising a relatively short platform adapted to support the edge of an inclined standing book and a back associated therewith and adapted 110 to support the side of the standing book, the upper receptacle being provided at the junction of the platform and back with a recess for accommodating a cover-section.

5. A loose-leaf book-supporting rack comprising a lower platform adapted to support a book on its side, and an inclined back, with a recess at the lower portion of said back for accommodating a cover-section, and an upper receptacle adapted to support 120 a book in inclined standing position and located substantially above the plane of the book space of the lower receptacle and comprising a rearwardly and downwardly-inclined relatively short platform and a rear- 125

130

wardly and upwardly-inclined back, said upper platform being provided at its base portion with a recess for accommodating a cover section.

- 5 6. A loose - leaf book - supporting device comprising a standard provided with an upwardly and rearwardly-inclined front surface, a lower platform extending in front of said inclined surface and adapted to support 10 a book on its side, the inclined surface of said standard being adapted to support the edge of the book, and an upper platform extending in front of said inclined surface, the upper platform being relatively short 15 and adapted to support a book on edge, the upper portion of the inclined surface of said standard being adapted to support the side of the book.

7. A loose-leaf book supporting rack having upper and lower receptacles and comprising a standard having a rearwardly and upwardly inclined front wall and a forwardly and upwardly inclined platform projecting in front of said inclined wall and 20 adapted to support a book on edge, and a larger forwardly and upwardly inclined lower platform projecting in front of said inclined wall adapted to support a book on its side, said inclined wall serving to support 25 30 the edge of a book in the lower receptacle and serving to support the side of a book in said upper receptacle.

8. A book-supporting rack for the purpose set forth, comprising a lower receptacle 35 adapted to support a book on its side and an upper receptacle superposed over the lower receptacle, the lower receptacle having a relatively short back wall and a relatively long bottom wall so disposed that the edge 40 of the book will bear normally against the back wall, and the upper receptacle having a relatively short forwardly and upwardly inclined bottom wall which projects over the book-space of the lower receptacle and 45 having a rearwardly and upwardly inclined back wall adapted to support the side of a book in inclined standing position with its edge resting on the bottom wall.

9. A book-supporting rack of the character set forth, comprising a lower receptacle 50 adapted to support a book on its side and an upper receptacle substantially superposed over the book-space of the lower receptacle and adapted to support a book in inclined standing position, the lower receptacle having a rearwardly and downwardly inclined bottom wall upon which a book may lie on its side and having a relatively short upwardly and rearwardly inclined back wall substantially at right-angles to the bottom 55 wall, against which the edge of the book may rest, and the upper receptacle having a forwardly and upwardly inclined relatively short bottom wall projecting over the book-space of the lower receptacle and having a 60 relatively long upwardly and rearwardly inclined back wall against which the side of the book in inclined standing position may rest, the back wall of the upper receptacle being substantially a prolongation of the 65 back wall of the lower receptacle.

10. A rack for the purpose set forth, comprising a lower front receptacle having a bottom wall upon which a book may lie flatwise and a back-wall for the edge of the 70 book, said walls being so disposed that a book will lie normally with its edge against said back-wall, and an upper rear receptacle comprising a relatively short bottom wall which projects over the book-space of the 75 lower receptacle and a back-wall which inclines rearwardly and upwardly, whereby said upper rear receptacle is adapted to support a book on edge substantially overlying the book-space of the lower receptacle. 80 85

11. A book-supporting rack of the character set forth, having an upper receptacle and a lower receptacle, comprising an inclined back, a lower platform extending in front of said back and adapted to support a 90 book on its side, and a relatively short upper extensible inclined platform extending in front of said back and projecting over the book-space of the lower receptacle.

GEORGE H. POTWIN.
